UNITED STATES PATENT OFFICE.

EPHIE COHEN, OF JOPLIN, MISSOURI.

ORE-JIGGER.

No. 894,604.

Specification of Letters Patent.

Patented July 28, 1908.

Application filed March 13, 1908. Serial No. 420,782.

To all whom it may concern:

Be it known that I, EPHIE COHEN, a citizen of the United States, and a resident of Joplin, in the county of Jasper and State 5 of Missouri, have invented certain new and useful Improvements in Ore-Jiggers, of which the following is a specification.

My invention is an improvement in ore jiggers and consists in certain novel constructions and combinations of parts as will 10 be hereafter described and claimed.

In the drawings Figure 1 is a top plan view of the apparatus. Fig. 2 is a vertical longitudinal section thereof on about line 15 2—2 of Fig. 1. Fig. 3 is a vertical cross section on about line 3—3 of Fig. 1. Fig. 4 is a detail view illustrating the yielding connection between one of the sieve hangers and the lever.

20 In carrying out the invention, I provide a tank 1, having at one end an inlet 2 for the ore, and the tank is preferably divided by a partition 3 into, what for convenience of reference, I term the sieve chamber 4 and the 25 discharge or settling chamber 5, water being supplied to the tank and ordinarily maintained at about the level of the water line indicated in Fig. 2 of the drawings. A frame 6 is mounted upon the tank and is provided 30 with bearings having a shaft 7 carrying eccentric disks 8 upon which fit the straps 9 having the rods 10 leading downwardly therefrom, and connected at their lower ends with the inner ends of levers A whose outer 35 ends are pivoted at 20 and whose inner ends extend adjacent to each other and connect with their respective rods 10 whereby the levers are rapidly oscillated as the eccentrics A are turned with the revolution of the 40 shaft, the latter turning at a comparatively rapid speed, usually about 140 revolutions per minute. These levers A are balanced somewhat by springs 11 upon rods 12 the said rods being secured at their lower ends 45 to their respective levers A, and extending thence upwardly through frame bars 13 and receiving the springs 11 which bear between the frame bars 13 and washers 14 of the rods 12, as best shown in Fig. 2 of the drawings.

50 The rods 12 connect with the levers A midway between the ends of the said levers, and near the pivoted ends of the levers I connect therewith the hangers B which are pivoted at their lower ends to the sieve C extend 55 thence upwardly through slots A¹ in the

levers A, and project above the levers and receive springs D, all arranged as best shown in Fig. 4 of the drawings. The purpose of these hangers B is to transmit the motion of the levers A to the sieve, and in this operation it will be understood that the levers A are raised and lowered by the action of the eccentrics and transmit motion through the hanger rods B to the sieve C. This motion however is not transmitted directly to the 60 said sieve but indirectly by virtue of the spring D.

The levers are slotted at A¹ for the passage of the hangers B so that the said hangers B can move longitudinally along the connection with the lever A, such connection being effected in each instance by means of a cross pin E passing through the lever A and operating in a slot B¹ in the hanger B. Above the slot B¹ the hanger B has a reduced portion B² and a spring D encircles this reduced portion and bears between a plate B³ at the upper end of the hanger B, and a plate B⁴ which bears below the spring D, rests upon the lever A and is slotted to permit the 70 hanger B to work up and down through it, it being understood that the hanger B works up and down through the plate B⁴ and the latter rests on the lever A.

In operation as the lever A is moved upward by the eccentric the spring D will be put under compression, and after the eccentric has moved the lever A to its highest position, the spring D will expand and give the sieve a still further upward movement, the 80 spring being thus relieved of tension. On the return stroke of the eccentric the spring D being relieved of tension the lever A will start downward and there will be a tendency resulting from the construction described for the 85 sieve C to be given a quick downward movement. In this operation as the spring D expands it will lift the hanger until the pin E is at the bottom of the slot B¹ so that when the lever A begins its downward movement the pin 90 E will be in such position. In this operation it will be understood the sieve will move up slowly and down quickly as is desired in this 95 class of apparatus.

To facilitate the passage of the ore from 100 above the sieve C in the operation of the invention I provide a carrier in the form of an endless apron having sprocket chains F carried over wheels F¹ one of which may be driven by the gearing G, and slats H connect- 110

ing the chains F and having suitable pins I which depend on the lower run of the carrier in the water above the sieve and moving in the direction of the arrow shown in Fig. 2, 5 serve to carry the ore from above the sieve towards the discharge chamber 5 both by positive contact with the ore and by setting up a current in the direction of the chamber 5, as will be understood by those skilled in 10 the art.

In pivoting the levers A at 10 it is preferred to mount them upon cross rods or shafts J, and the said levers A are deflected at their inner ends, as best shown in Fig. 1, 15 so they may be brought directly below their respective eccentrics, as will be understood from Figs. 1 and 3 of the drawings. An outlet cock 15 may be provided for draining the chamber 5 and outlets 24 having valves 25 20 are provided leading from the bottom of the chamber 4, as shown in Figs. 2 and 3 of the drawings.

I claim—

1. An ore jigger comprising a tank, and 25 sieve movable up and down in the tank, levers pivoted at their outer ends and extending inwardly over the sieve, rods connected with the levers and extending upwardly therefrom, springs on said rods, eccentrics, 30 straps on said eccentrics and having rods connected with the inner ends of said levers, the levers being provided near their pivoted ends with vertical openings, hangers connected at their lower ends with the sieve and extending 35 upwardly through the openings in the levers and having slots within the openings or slots of the levers, pins passing through the slots in the hangers and connected with their respective levers, springs on the upward extension of the hangers and bearing between the levers and abutments on the said upward 40 extension of the hangers and a carrier operating between the levers and the sieve, all substantially as and for the purpose as set 45 forth.

2. In an ore jigger the combination with the tank and sieve movable up and down therein and the levers for operating the sieve, of hangers connected with the sieve and provided between their ends with vertically elongated slots, pins passed through said slots and connected with the levers, the hangers being provided with extensions above the levers and springs on said extensions and bearing between the same and the 50 levers, substantially as set forth.

3. The combination in an ore jigger substantially as described of a tank and sieve movable up and down in the tank, levers pivoted at their outer ends and extending inwardly over the sieve, rods connected with the levers and extending upwardly therefrom, springs on said rods, eccentrics, straps on said eccentrics and having rods connected with the inner ends of said levers, the levers 60 being provided near their pivoted ends with vertical openings, hangers connected at their lower ends with the sieve and extending upwardly through the openings in the levers and having slots within the openings of the 65 levers, pins passing through the slots in the hangers and connected with their respective levers, and springs on the upward extension of the hangers and bearing between the levers and abutments on the said upward extension of the hangers, substantially as described.

4. The combination of a sieve, levers for operating the sieve and pivoted at one end, means connected with the other ends of said 70 levers for oscillating the same, hangers between the sieve and their respective levers and yieldingly connected with the latter, rods connected with the levers and extending upwardly therefrom, and springs on said 75 rods substantially as set forth.
